FOREIGN PATENT DOCUMENTS

CA 2615294 A1 6/2009

Primary Examiner — Sandra Snapp*Assistant Examiner* — Ieisha N Price(74) *Attorney, Agent, or Firm* — Greer, Burns & Crain, Ltd.(57) **CLAIM**

The ornamental design for a rod coupler, as shown and described.

DESCRIPTION

FIG. 1 is a front view of the present rod coupler;
 FIG. 2 is a right side view of the rod coupler of FIG. 1;
 FIG. 3 is a left side view of the rod coupler of FIG. 1;
 FIG. 4 is a bottom view of the rod coupler of FIG. 1;
 FIG. 5 is a rear view of the rod coupler of FIG. 1;
 FIG. 6 is a top perspective view of the rod coupler of FIG. 1; and,
 FIG. 7 is a top view of the rod coupler of FIG. 1.
 The broken lines in the drawings illustrate portions of the rod coupler which form no part of the claimed design.

1 Claim, 7 Drawing Sheets(56)
